UNITED STATES PATENT OFFICE

S. SAGUE VIDETTO, OF MINATARE, NEBRASKA

ROTARY ENGINE

Application filed June 21, 1926. Serial No. 117,433.

My invention relates to improvements in rotary engines, and it consists in the combinations, constructions, and arrangements herein described and claimed.

5 An object of my invention is to provide an improvement over that form of the device shown in my co-pending application for patent on rotary engine, Serial No. 713,844, filed May 16, 1924.

10 A further object of my invention is to provide a rotary engine of the type described in which particularly novel means is employed for providing a power impulse effective during substantially 290 degrees of rotation of the rotor. This is a highly important

15 advantage, and provides for the smooth, uniform, rotation of the rotor shaft, highly desirable in engines of all characters. This is accomplished by the use of an abutment valve,

20 the movement of which is practically instantaneous upon the approach of the rotor piston thereto, so as to permit the piston to pass over that portion of the stator occupied by the valve. The return of the valve to its operative

25 position is effected with the same and for all purposes practically instantaneous movement upon the rotor piston therebeyond. At this time the abutment valve actually contacts with the inclined surface of the rotor piston.

30 A further object of my invention is to provide a device of the type described in which mechanism is employed for bringing about positive operation of the abutment valve. I have found it necessary that the valve open

35 and close at exact periods in the rotation of the rotor, and that the forces operating the valve be positive forces, not those such as exerted by a spring or the like, which might easily become inefficient through wear, subjection to heat, etc.

40 A further purpose of providing positive operating means for actuating the abutment valve is that the valve may operate regardless of the position of the engine. It will be apparent from the foregoing description that the engine will operate just as efficiently in an inverted position as in an upright position. For this reason, my improved rotary engine may be adapted for use when bolted

50 to a side wall or ceiling.

A further object of my invention is to provide a rotary engine of the type described in which the packing between the rotor and stator is arranged in a particularly efficient manner, so as to preclude the jamming of the rotor packing strip with the stator packing strip. This feature of my invention I deem an important one, and I have overcome a disadvantage possessed by practically every type of engine employing radially disposed packing elements on the rotor-stator members.

55 A further object of my invention is to provide a rotary engine of the type described which may be coupled with other like engines on a single shaft to provide a complete power unit in which there is no dead center.

60 Other objects and advantages will appear in the following specification, and the novel features of the invention will be particularly 65 pointed out in the appended claims.

70 My invention is illustrated in the accompanying drawings, forming part of this application, in which

75 Figure 1 is a plan view of the device,

Figure 2 is a side elevation of the device showing the abutment valve opening cam,

Figure 3 is a side elevation of the device showing the closing cam and timing gears,

80 Figure 4 is a section substantially along the line 4—4 of Figure 3,

Figure 5 is a section substantially along the line 5—5 of Figure 4,

85 Figure 6 is a section along the line 6—6 of Figure 1,

Figure 7 is a section along the line 7—7 of Figure 6,

Figure 8 is a detail face view of a portion of the valve 59 later described.

90 Figure 9 is a section along the line 9—9 of Figure 7,

Figures 10, 11 and 12 are detail views of the steam packing,

95 Figures 13, 14 and 15 are diagrams illustrating the positions of the closing and opening cams during an operation of the abutment valve,

100 Figures 16, 17 and 18 are diagrams of the rotary multiple-port valve, illustrating posi-

tions corresponding with the respective foregoing diagrams,

Figure 19 is a detail perspective view of the cam shaft and its cams, and

5 Figure 20 is a perspective view of the L-shaped packing strips.

In carrying out my invention, I make use of a stator 1 having removable end plates 2 and 3 at the opposite ends thereof and secured 10 thereto by means of bolts 4. The stator 1 is supported upon a suitable base 5.

A rotor 6 consisting of a hollow drum is keyed to a shaft 7. The shaft 7, see Figure 4, is rotatably mounted in bearing portions 8 formed in the end plates 2 and 3, respectively. Suitable packing 9 and adjustable glands 10 are provided in the bearing members 8 for preventing the escape of steam through the bearings. The rotor 6, see Figure 20, is provided with a piston 11 extending radially from the peripheral wall of the rotor to a point closely adjacent to the inner wall 12 of the stator. For the present, I will not describe the packing I employ between 25 the stator and the rotor. The shaft 7 is free to rotate so that the rotor 6 may continuously rotate within the stator.

A throttle valve chamber 13 is formed integral with the stator 1 and is provided with 30 a steam port 14. An inlet port 15 is provided and communicates with the interior of the stator 1 at a point adjacent to the horizontal axis of the stator. A valve 16 is rotatably mounted within the chamber 13. The construction of this valve is clearly shown in Figure 5, and is such as to permit the steam to pass from the steam port 14 through the chamber 13, and through the inlet port 15 into the stator when turned to the position shown in full lines in Figure 5, but to stop the flow of steam through the inlet port when turned to the position shown in dotted lines in Figure 5. A valve stem 17 is provided for the valve 16 and extends through an elongated end plate 18 employed for closing one end of the chamber 13, and serving as a bearing for the valve stem 17. The opposite end of the chamber 13 is closed by an end plate 19. Means for operating the valve 16 is provided by the use of an eccentric 20 mounted upon the shaft 7 and operatively secured to the valve stem 17 by a crank 21 and an adjustable rod 22. A rotation of the shaft 7 will cause an opening and closing of the valve 16 by an oscillatory movement of the valve stem. An exhaust port 23 is provided in the stator 1, as clearly shown in Figures 4 and 5.

A horizontal abutment valve chamber 24 is disposed upon one side of the stator at a point directly beneath the valve chamber 13. The ends of the chamber 24 are closed by integral extensions of the end plates 2 and 3. A cover plate 25 is disposed over the chamber 24, and extends from the extension

of the end plate 2 to the extension of the end plate 3, and is rigidly secured thereto. An abutment valve 26 is provided with integral runners 27 on each side thereof which are slidably disposed within horizontal slots 28 in the end plates 2 and 3. The slots 28, which extend tangentially from the shaft 7 to the cover plate 25, divide the space between the rotor 6 and the stator 1 into two parts, whereby an expansion chamber is formed. The abutment valve 26 has an inclined surface 29 which is substantially in alignment with the inlet port 15. The piston 11 has an inclined surface 30 which corresponds with the inclined surface of the abutment valve 26. The abutment valve 26 is provided with two adjustable rods 31 which extend through the cover plate 25 and are secured to a crosshead 32, see Figure 1.

A rocker shaft 33 is disposed beneath the valve chamber 24 and extends outwardly a short distance beyond each of the end plates 2 and 3. On each end of the rocker shaft 33, a double crank 34 is mounted. The cranks 34 are each provided with studs 35 and 36. An adjustable rod 37 is pivotally mounted upon each end of the crosshead 32, the free end of each rod being secured to its respective crank 34 by means of the stud 35. These rods also serve to limit the inward movement of 95 the abutment (Fig. 2) when extended as far as possible along their paths of arcuate movements by the cranks 34.

In order that I may use the power impulse effectively up to the very moment 100 that the piston 11 closely approaches the abutment valve 26, it is necessary that some means be provided for moving the abutment valve substantially instantaneously to the outermost position in the valve chamber 24. Obviously the rotation of the shaft 7 is too slow for the actuation of cams associated therewith and employed for this purpose. I have therefore provided a cam shaft 38 (Figs. 1 and 3) which is slidably and rotatably mounted 110 in an elongated bearing 39.

A drive gear 40, secured to the main shaft 7, drives a pinion 41 fixed upon the cam shaft 38. The pinion is one-half the diameter of the gear 40 with the effect that the cam shaft will make two revolutions for every one revolution of the main shaft. The necessity for gearing the cam shaft 38 to a higher speed than the main shaft 7 is to obtain a quick movement of the abutment 115 26. The pinion 41 is substantially twice the width of the gear 40, so that the cam shaft 38 may be slid longitudinally without losing its engagement with the drive gear.

The shaft 38 carries a pair of cams individually known as the closing cam 90 and the opening cam 91 (Fig. 19). The former is relatively near to the pinion 41 (Fig. 1), the latter being at the remote end of the cam shaft. As their names imply, these cams are 120

identified with corresponding movements of the abutment valve 26 (Fig. 5) in respect to the working chamber of the stator. The closing cam will assist and permit a movement of the abutment valve into the working chamber, while the opening cam will similarly assist and permit a movement of the abutment valve outwardly of the working chamber. Power for these movements of the abutment valve is primarily derived from a steam-operated actuating device presently described.

These cams have what may be known as idler rims 92 and 93. The rim 92 appears as a disc when viewed from one end of the engine (Fig. 3). The rim 93 appears as a hub (Fig. 2) and is the same in diameter as the valley 94 of the closing cam 90. In effect the cam 90 is formed on back of a sufficiently thick disc while the cam 91 is formed on one side of a circular hub. Thus the so-called disc and hub present bodies that are thicker than the cams themselves, the purpose presently becoming evident.

Rollers 44 and 44' ride upon either the cams 90 and 91 or upon the idler rims 92 and 93, depending on whether the cam shaft 38 has been slid forwardly in the direction of the observer (Fig. 3) or rearwardly. Figure 1 shows the cam shaft 38 slid to the limit of its forward movement, but it will presently be slid rearwardly in order to bring the rollers 44 and 44' within range of the idler rims 92 and 93, because the abutment valve 26 is supposed to have just been closed (Fig. 5) and it is the function of the engagement of the idlers with the continuous idler rims to firmly hold the abutment valve in engagement with the rotor 6.

The utility of the idler rims 92 and 93 and the necessity of the shaft 38 being made slideable longitudinally by eccentric 47 and associated parts will be considered together. Gear wheel 40 on main shaft 7 being twice the diameter of pinion 41 on cam shaft 38, it is evident that shaft 38 will make two revolutions to each revolution of main shaft 7. It is further evident that as there is but one piston on rotor 6, abutment 27 should be operated but once to each revolution of shaft 7, or once to two revolutions of shaft 38.

It is further evident that as abutment is to be operated but once to two revolutions of shaft 38, cams 90 and 91 must be in some way moved out of contact with rollers 44 and 44' during each alternate revolution of cam shaft 38, hence, the need of eccentric 47 and associated parts. Roller 44, while riding on idler rim 92, holds abutment 27 in contact with rotor 6, idler rim 93 provides a plate for roller 44' to ride on, while roller 44 rides on rim 92, thus both rollers are at all times in contact with either their cams or idlers and are at no time held suspended as would be the case if idlers were not provided.

The rollers 44 and 44' are pivotally mounted upon bell crank levers 45 and 45' (Figs. 1, 2 and 3). These bell crank levers are fulcrumed upon the end plates 2 and 3. The otherwise free arms of the bell cranks have adjustable rods 46 and 46' connected therewith, the free ends of these rods being pivotally attached to the studs 36 of the cranks 34, mentioned before.

An eccentric 47, fixed on the main shaft 7, has a strap with means for sliding the cam shaft 38. The sliding occurs first in one direction, then in the other, during approximately 70 degrees of rotation of the main shaft 7, this operation being repeated during each revolution of the shaft. That means comprises a socket 48. A bell crank 49, pivotally mounted upon a bracket 51 on the end plate 3, has a ball-shaped end 50 fitting in the socket, and a forked end 52 with confronting pins 53 engaging a sleeve 54 between adjustable rings 55 on the cam shaft. Periodic operation of the eccentric 47 and its appurtenances, will slide the cam shaft 38 first forwardly to bring the rollers 44 and 44' within range of the cams 90 and 91 as when the abutment valve 26 is to be open, then rearwardly to return the rollers to the idler rims 92 and 93 after the abutment valve has again closed. The closing and opening cams are in such angular relationship to the cam shaft 38 (Figs. 13, 14 and 15) that the sliding movements of the cam shaft 38, especially the rearward sliding motion, will not cause a jamming against the rollers 44 and 44'.

Mention has been made of a steam-operated actuating device for moving the abutment valve 26. This device and the cam mechanism work together in opening and closing the abutment valve, but said device does the actual work of shifting the abutment, thus relieving the cams 90, 91 and the accompanying parts of the strain. The function of the cams is to hold the abutment valve in perfect control at all times, and to positively hold said abutment valve in contact with the rotor. The actuating device comprises a cylinder 56 (Figs. 1, 6 and 7) which is fixed upon the cover plate 25 mid-way between the adjustable rods 31.

A piston 57 reciprocable in the cylinder 56 has a rod 95 connected with the cross head 32. The admission of steam to opposite ends of the cylinder 56 in alteration will move the cross head first to the left, then to the right, to withdraw and return or, in other words, to open and close the abutment valve 26. A steam chest 58, disposed beneath the cylinder 56, has a rotary multiple-port valve 59 which turns against an inserted valve seat 60. Steam passages 61 and 62 (Fig. 6) alternately conduct live steam to the opposite ends of the cylinder 56, and also conduct exhaust steam from such ends.

so that the movements of the piston 57 will be permitted.

The rotary valve 59 has six sets of live steam ports (Figs. 8, 16, 17 and 18). It also has six sets of exhaust ports. The various ports are arranged upon two circles which are of sufficiently different diameters to bring the ports within range of the steam passages 61 and 62. Those of the live steam ports in the inner circle within range of the passage 61 are designated 63. Corresponding exhaust ports are designated 64. Those of the live steam ports within range of the steam passage 62 are designated 96, corresponding exhaust ports being designated 97. The exhaust ports communicate with a passageway 98 within the valve 59, the valve, in other words, being hollow. The exhaust ports occur only in the inner concealed wall 20 of the valve, but the live steam ports 63 and 96 extend all the way through, to which end these ports occur in solid portions of the valve disc.

A relatively large opening 65 in an extension 99 of the valve 59 communicates with the passageway 98 and conducts exhaust steam to an appropriate outlet 100. The extension 99 serves as a bearing. The perimeter of the valve may be kept free of the cylindrical wall of the steam chest, but the inner concealed side of the valve must bear closely against the seat 60 so that there may be no undue escape of steam.

The valve 59 is provided with a shaft 66 which extends through the steam chest 58, see Figure 7. Suitable packing 67 and an adjustable gland 68 are provided in the steam chest 58 for preventing escape of the steam around the shaft 66. A ratchet wheel 69 is keyed to the end of the shaft 66. A lever 70 is disposed upon each side of the ratchet wheel 69 and rotatably mounted upon the shaft 66. A spring-pressed pawl 71 is mounted between the levers 70, and is in engagement with the ratchet wheel 69. The levers 70 are pivotally secured to an adjustable bar 72. The free end of the bar 72 is secured to an eccentric 73 which is mounted upon the shaft 7.

Means for packing the rotor-stator contact and the abutment contact with the rotor and stator walls is provided in the following manner: The slot 28, in which slide members 74 of the abutment 26 operate, is extended directly into the opening of the end plates 2 and 3, respectively, through which the shaft 7 is projected. It will be noted from an inspection of Fig. 10 that the outermost wall 75 of the slot 28 is nearly tangent to the peripheral wall of the opening 76 in the plates 2 and 3, respectively, through which the shaft 7 is projected. The slot 28 is not disposed radially from the center of the opening 76.

Spring-pressed packing strips 77, each held in position by a dowel 77a (Fig. 10), are disposed in the lowermost ends of the slots 28

and extend from the shaft 7 outwardly as far as the peripheral edge 78 of the rotor, see Figure 10.

In order to prevent the loss of power by steam escaping from the expansion chamber to the exhaust port 23, I employ in the rotor 6 and the piston 11, two L-shaped spring-pressed packing strips 79, see Figure 10, disposed in slots in the ends of the rotor and the piston, and extending radially from the shaft 70 to and across the peripheral wall of the piston. The two packing strips are joined to each other by a spliced joint, as shown at 86 (Fig. 12). The portions A (Fig. 11) of these packing strips which extend radially from the shaft 7 are made rectangular. The portions B which extend across the peripheral wall of the piston are dovetailed in cross section, and are disposed in slots 83 loose enough to be forced into contact with the interior surface of the peripheral wall of the stator.

The innermost end of the abutment 26 is provided with a spring-pressed packing strip 87 similar in cross-sectional contour to that portion of the L-shaped strips 81 disposed upon the outermost wall of the piston 11, and is fitted in a groove having the shape of the cross-sectional contour of the packing strip. A second spring-pressed packing strip 88 is disposed across the uppermost wall across each end of the abutment 26 and is arranged to engage with the adjacent wall of the opening 24.

The operation is readily understood. It is assumed that the engine is properly connected at 14 to a suitable source of steam, and that the piston 11 of the rotor 6 is in the position shown in Figure 5. The position of the parts shown here indicate that the abutment valve 26 has just been projected into the working chamber to the closed position. In Figure 1 the cam shaft 38 is about to be moved upwardly, or rearwardly when the observer assumes the position in Figure 3, and when the cam shaft is so moved the rollers 44 and 44' will ride upon the continuous idler rims 92 and 93 (Fig. 19), firmly holding the abutment valve against the rotor.

Steam will be admitted to the working chamber by way of the inlet port 15 (Fig. 5). The rotor 6 will be driven in the clockwise direction. The cam shaft 38 will be driven in the counter clockwise direction by virtue of the interposed gearing (Figs. 1 and 3). Assume that the piston 11 has traversed the working chamber to a point adjacent to the exhaust ports 23. The abutment valve 26 must be withdrawn or opened to permit passage of the piston. The closing cam 90 and opening cam 91 will now assume the relationship to the rollers 44 and 44' shown in Figure 13.

The roller 44 is riding high on its rim 92 while the roller 44' is riding low on its rim 93. A forward shift of the cam shaft 38

now occurs, bringing the parts to the relationship shown in Figure 1. Continued turning of the cam shaft will permit the roller 44 to ride down the cam 90 into the valley 94 (Fig. 14), while the cam 91 will elevate the roller 44' to the highest point. There has been an exchange in the positions of the rollers 44 and 44', but by tracing the articulated connections between the bell cranks 45 and 45' and the cross head 32 (Figs. 1, 2 and 3), it will be found that the movements are so co-ordinated that an outward movement of the cross head is permitted.

But the actual work of moving the cross head and of the abutment valve 26 is performed by the actuating device 57. The rotary valve 59 of this device assumes the position in Figure 16 during the moment now under consideration, namely, while the abutment valve 26 is still closed but is about to be opened. Certain ones of the ports 97 and 96 are designated A, B and C, while certain ones of the ports 63 and 64 are designated D, E and F.

Exhaust port A registers with the steam passage 62; live steam port B and exhaust steam port C are idle. Live steam port D registers with the steam passage 61, while ports E and F are idle. The registration of the port D and passage 61 provide for the presence of live steam in the left end of the cylinder 56 up to the present time, insuring the holding of the piston 57 as an auxiliary of the function of the cams already mentioned.

Still leading up to the opening of the abutment valve 26, the eccentric 73, (Fig. 1) will begin imparting a turn to the valve shaft 66. The stroke of the eccentric is such that the pawl 71 (Fig. 9) will turn the shaft 66 one-sixth of a revolution. The first half of this turn will advance the ports A to F to the positions in Figure 17. The formerly idle live steam port B will register with the passage 62 and admit steam to the right end of the cylinder 56, driving the piston 57 over and retracting the abutment valve 26 from the working chamber. Exhaust steam from the left end of the cylinder 56 escapes through the exhaust port E which now registers with the passage 61. The piston 11 will pass, and the rollers 44 and 44' approximately still assume the position in Figure 14.

The second half of the foregoing turn of the valve shaft 66 will complete the advancement of the ports A to F to the position in Figure 18. The formerly idle steam port F now registers with the passage 61 to admit steam to the left end of the cylinder 56. This drives the piston 57 to the right and closes the abutment valve 26 behind the piston 11 which has made its transition at the same time the exhaust port C registers with the passage 62 so that residual steam in the right

end of the cylinder 56 is permitted to pass out ahead of the piston.

Simultaneously with these operations the cams 90 and 91 will have advanced sufficiently far to raise the roller 44 from the valley 94, and to permit the lowering of the roller 44' to the level of the rim 93. This is the position shown in Figure 1, and it will be but an instant when the eccentric 47 will shift the cam shaft 38 upwardly or rearwardly so that the rollers can ride upon the continuous idler rims 92 and 93. It is important to observe that the rearward shift of the cam shaft 38 will not occur until the rollers 44 and 44' have been restored to their respective high and low levels (Fig. 15) at which time the rims 92 and 93 can be shifted thereunder without danger of binding. It is also to be observed that the forward shifting of the cam shaft 38 does not occur until the cams 90 and 91 (Fig. 13) have almost traveled around in a position to receive the rollers.

By virtue of the arrangement of the cams 90 and 91 the abutment valve 26 will be mechanically held in either the closed or open position. This holding is independent of the corresponding function that the actuating device 57 performs. Were the latter depended upon, the cutting off of steam at the port 14 would leave such an insufficiency of steam pressure that the abutment valve 26 might not properly be withdrawn from the working chamber by the time the piston 11 were about to pass over. At such a time the opening cam 91 would not only positively displace the abutment valve, but would hold it displaced for a proper period.

The movement of the abutment 26 is practically instantaneous, due to the fact that the cams operating the valve are actuated by a shaft rotating at twice the speed of the engine shaft, and that the opening and closing of the abutment is accomplished by positive means.

A very important advantage provided in my rotary engine is that regardless of the speed at which the rotor is traveling, there is no possibility of the jamming between the rotor and stator packing. This advantage is obtained through the particularly novel arrangement of the packing strips 77 and 79. An inspection of Figure 10 will show that the packing strip 79, see dotted lines, first contacts with the packing strip 77 on the stator at a single point 77b adjacent to the shaft 7, where travel is at its minimum. This part of the packing strip 77 is beveled slightly at 77c (Figs. 5 and 10) and thereby permits the strip 79 to ride thereupon without jamming. The tangential and radial relationship of the packing strips 77, 79 (Fig. 10) enables the crossing of the strip 79 in continuously biased positions during turning of the rotor with no possibility of the strip 79 lodging in the slot 28, which it might do if the slot 28 and

strip 79 were radial respecting the shaft. There is therefore no possibility of jamming between the packing strips, and greater force may be applied by the springs for adjusting 5 the strips than in the ordinary type of packing strips employed with engines of this character.

I claim:

1. A rotary engine comprising a stator, a 10 rotor rotatably mounted in said stator, a piston rigidly mounted upon said rotor extending radially therefrom and engaging with the inner walls of said stator, an abutment, steam-actuated means for moving said abutment 15 into and out of engagement with said rotor, and positive means for rigidly holding said abutment in engagement with said rotor until said rotor reaches a predetermined point in its rotative travel.
2. A rotary engine comprising a stator, a 20 rotor rotatably mounted in said stator, a piston rigidly mounted upon said rotor extending radially therefrom and engaging with the inner walls of said stator, an abutment, means 25 for moving said abutment into engagement with said rotor and out of engagement with said rotor and said piston, an auxiliary shaft driven by said rotor at a higher speed than said rotor, cam-actuated means actuated by 30 said auxiliary shaft for moving said abutment into and out of engagement with said rotor as said piston moves away from and approaches said abutment, respectively, during the rotation of said rotor, said piston 35 having its abutment-engaging surface inclined with respect to the intersecting radii of said rotor, and positive means for rigidly holding said abutment in engagement with said rotor up to a predetermined point in 40 the rotation of said rotor.
3. A rotary engine comprising a stator, a 45 rotor rotatably mounted in said stator, a piston rigidly mounted upon said rotor extending radially therefrom and engaging with the inner walls of said stator, an abutment 50 carried by said stator, steam-actuating means for moving said abutment into and out of engagement with said rotor, and cam-operated means for positively and rigidly holding said abutment in engagement with said rotor during 55 a predetermined portion of the rotative travel of said rotor.
4. In a rotary engine having a circular stator with an inner wall and lateral end walls, 60 a shaft, a circular rotor carried by said shaft, and a piston having end walls and an outer wall being carried by said rotor, means for forming a tight connection between said rotor, said piston and said stator, said means 65 comprising packing strips located in grooves in the end walls of said stator and disposed tangentially of said shaft, packing strips extending radially from said shaft and disposed in the end walls of said rotor and said 70 piston, said last named packing strips having

portions extending inwardly at right angles and receivable in a groove in the outer wall, means carried by said portions for interlocking, and spring means for holding said packing strips outwardly.

5. A rotary engine comprising a stator defining a working chamber, a rotor revoluble therein and having a piston, an abutment valve movable into and out of the working chamber, fluid-operated means to actuate the abutment valve, and means working in consonance with said fluid-operated means following the movements of the abutment valve and fixedly holding it in contact with the rotor when closed.

6. A rotary engine comprising a stator defining a working chamber, a rotor revoluble therein and having a piston, an abutment valve, fluid-operated means for moving the abutment valve into and out of the working chamber into closed and open positions, a pair of cams respectively associated with the closing and opening movements of the abutment valve, and articulated connections between the cams and said fluid-operated means, working in consonance with the latter to permit the opening and closing movements but serve to positively hold the abutment valve either closed or open after the respective movements have been completed.

7. A rotary engine comprising a stator defining a working chamber, a rotor revoluble therein having a piston, an abutment valve, fluid-operated means for moving the abutment valve into and out of the working chamber into closed and open positions, said means including a cross head carrying the abutment valve, a pair of cams respectively associated with said closing and opening movements, and articulated connections having certain members connected with the cross head and other members co-acting with the cams, working in consonance with the cams and cross head upon closing and opening movements, but being acted upon by the cams to positively hold the abutment valve either closed or open after the movements have been accomplished.

8. A rotary engine comprising a stator defining a working chamber, a rotor revoluble therein having a piston, an abutment valve, fluid-operated means for moving the abutment valve into and out of the working chamber into closed and open positions said means including a cross head carrying the abutment valve, a pair of cams having associated continuous idler rims, articulated connections joining the cross heads with the cams including bell cranks having rollers adapted to ride upon the cams in consonance with the closing and opening movements of the cross head, and means to shift the cams and rims causing the rollers to ride upon the rims after a closing movement of the cross head to positively hold the abutment valve against

the rotor independently of said fluid-operated means.

9. A rotary engine comprising a stator defining a working chamber, a main shaft having a rotor revoluble in the working chamber, a piston on the rotor, an abutment valve, fluid-operated means operable by fluid from the same source that supplies the working chamber to move the abutment valve into closed and open positions, closing and opening cams having means associated therewith and with the fluid-operated means, permitting said closing and opening movements but positively holding the abutment valve withdrawn from the stator during a comparatively short open interval, and means for positively operating the cams from the main shaft insuring co-ordinated operation between the piston and abutment valve.

10. A rotary engine comprising a stator, a main shaft having a rotor revoluble in the stator, the rotor carrying a piston, a cam shaft, means operated by the cam shaft to periodically slide the cam shaft back and forth, means to drive the cam shaft from the main shaft but permit said sliding movements, a cam on the shaft having an adjacent circular idler rim, an abutment valve, means to move it into closed and open positions, and articulated connections from the abutment valve to the cam including a roller riding on the cam during periods of movement of the abutment valve but on the rim to insure the closure of the abutment valve after movement has ceased.

11. In a rotary engine, a stator having a working chamber, an abutment valve movable into closed and open positions in respect to the working chamber, a roller having articulated connections with the abutment valve, a cam upon which the roller rides during an opening and closing movement of the abutment valve, and an idler rim with which the roller is brought into engagement after the closing movement of the abutment valve to hold the latter in said position for a predetermined period.

12. In a rotary engine, a stator having a working chamber, an abutment valve movable into closed and open positions in respect to the working chamber, a roller having articulated connections with the abutment valve, a cam upon which the roller rides during an opening and closing movement of the abutment valve, an idler rim with which the roller is brought into engagement after the closing movement of the abutment valve to hold the latter in said position for a predetermined period, and means to periodically shift the cam and rim together so that the roller may alternately be within range of the cam and the rim.

13. In a rotary engine, a stator having a working chamber, bearing means carried by the stator, a revoluble cam shaft journaled in

the bearing means, an abutment valve movable to closed and open positions in respect to the working chamber, means connected with the abutment valve terminating in a roller, a cam on the cam shaft having an associated circular idler rim, and means for periodically sliding the cam shaft in its bearing means to bring the cam within range of the roller during opening and closing movements of the abutment valve, and the rim within range of the roller after the valve has closed to hold it in said position in the working chamber.

14. In a rotary engine, a working chamber, a movable abutment, fluid-operated moving means for moving the abutment into and out of the working chamber, a pair of linkage systems joined at one end to the moving means, and double-acting revoluble cams controlling the other ends of the linkage systems, said cams acting through said linkage systems to limit the inward and outward movements of said abutment and having contours producing motions in the linkage systems in consonance with the motions of the moving means.

15. In a rotary engine, a working chamber, a movable abutment, fluid-operated moving means for moving the abutment into and out of the working chamber, a pair of linkage systems joined at one end to the moving means and terminating in rollers at the other end, and a pair of revoluble opening and closing cams, upon which the rollers bear, one comprising a lobe and the other having a valley, respectively causing the rollers to ride up and down thus producing motions in the linkage systems in consonance with the motions of the moving means, and checking the movement of the abutment and limiting its position at the end of each stroke.

16. In a rotary engine, a working chamber, a movable abutment, fluid-operated moving means for moving the abutment into and out of the working chamber, a linkage system including a rod joined to said moving means, means actuating the linkage system thereby to check the movements of the abutment, and a turnable crank included in said system, with which crank the rod is also joined, said rod limiting the inward movement of the abutment when said rod is extended as far as possible along its path of arcuate movement with the crank.

17. In a rotary engine, a stator having an end wall with a shaft opening and a slot tangential to the opening, a rotor having an end wall with a radial slot, and packing strips occupying said slots, the tangential relationship of the first-named slot to said shaft opening avoiding radial registration of the slots and packing strips.

18. In a rotary engine, a stator end wall having a shaft opening and a slot tangential to the opening, a rotor and piston having a

radial slot situated in the wall adjoining the stator wall and extending from the shaft opening to the approximate end of the piston, a packing strip in the tangential slot extending from the shaft opening to the peripheral line of the rotor, and a packing strip located in and approximately coextensive with the radial slot, the tangential relationship of the first-named slot to said shaft opening avoiding radial registration of the slots and packing strips.
